UNITED STATES PATENT OFFICE.

HENRY O. SCHMIDT, OF NEW YORK, N. Y., ASSIGNOR TO THE LANDERS, FRARY & CLARK, OF NEW BRITAIN, CONNECTICUT.

DESIGN FOR A CAP FOR CUTLERY-HANDLES.

SPECIFICATION forming part of Design No. 25,269, dated March 24, 1896.

Application filed February 20, 1896. Serial No. 580,132. Term of patent 7 years.

To all whom it may concern:

Be it known that I, HENRY O. SCHMIDT, a citizen of the United States, residing at New York, in the county of New York and State 5 of New York, have invented and produced a new and original Design for a Cap for Cutlery-Handles, of which the following is a specification, reference being had to the accompanying drawings, in which—

10 Figure 1 is a face view of a cap for the butts of cutlery-handles, showing my design. Fig. 2 is an edge view thereof.

The cap is of an oval form in face or front view and is ornamented mainly by a combined leaflet and scroll ornament, near the 15 edge, surrounding an open field.

The edge 3 of the cap is slightly beveled,

as shown, and the face of the cap is rounded, so as to project at the middle portion, as shown by the edge view, Fig. 2. Near the 20 edge, on each of the longer sides, is a series of slightly-curved leaflets 4, with their points turning inwardly, the same running into and combining with the more abruptly-curved leaflets or scrolls 5 at the ends or shorter sides 25 of the cap, leaving a plain central open field of substantially an oval form, all as shown.

What I claim is—

The design for a cap for cutlery-handles substantially as illustrated and described.

HENRY O. SCHMIDT.
